SAMUEL A. BLAKE, OF MILFORD, CONNECTICUT.

Design No. 3,019, dated May 12, 1868.

DESIGN FOR AN IMITATION BRAID FOR BONNETS, &c.

The Schedule referred to in these Letters Patent and making part of the same.

TO ALL WHOM IT MAY CONCERN:

Be it known that I, SAMUEL A. BLAKE, of Milford, in the county of New Haven, and State of Connecticut, have invented a new Design for Imitation Braid for Bonnets, &c.; and I do hereby declare the following, when taken in connection with the accompanying drawing, to be a full, clear, and exact description, and which said drawing constitutes part of this specification, and represents a specimen of the imitation braid.

This design relates more especially to the manufacture of head-coverings from cloth or similar material, the object being to emboss the said coverings to represent a braided material; and the invention consists in the peculiar configuration or form of the braid imitated.

This peculiar form or design of braid is clearly represented in the specimen hereto attached.

I claim as my invention, and desire to secure by Letters Patent—

The design for imitation braid herein set forth and shown.
